F. J. HOFSCHEIDER

DEVICE FOR DENTAL USE

Filed June 13, 1922

INVENTOR
Frederic J. Hofschneider

Harold E. Stonebraker,
his ATTORNEY

UNITED STATES PATENT OFFICE.

FREDERIC J. HOFSCHEIDER, OF ROCHESTER, NEW YORK.

DEVICE FOR DENTAL USE.

Application filed June 13, 1922. Serial No. 568,055.

To all whom it may concern:

Be it known that I, FREDERIC J. HOFSCHEIDER, a citizen of the United States, residing at Rochester, in the county of Monroe and State of New York, have invented certain new and useful Improvements in Devices for Dental Use, of which the following is a specification.

My invention relates to a device for dental use, and more particularly has for its purpose to afford a structure useful in conjunction with a dental engine for furnishing a continuous supply of fluid, either water or air, together with electrical means for readily and quickly opening or shutting off the fluid supply.

In a more specific aspect, the invention has for one of its purposes to maintain a continuous supply of water to a grinding wheel or other abrasive element used on a dental engine hand piece, and to automatically start the water supply upon closing the circuit to the motor which operates the engine, while cutting off the water supply as the motor is stopped.

The invention also embraces certain other detailed features, all of which will appear clearly from the following description, when read in conjunction with the accompanying drawing, the novel features being pointed out in the claims following the specification.

In the drawing:

Figure 1 is a view in elevation, partially broken away, showing a preferred embodiment of the invention, and its application to a conventional style of dental hand piece;

Figure 2 is a vertical sectional view of the electrical valve controlling device and part of the fluid conducting means;

Figure 3 is a detail sectional view of the valve and valve seat, and

Figure 4 is a diagrammatic view of the electric circuit governing the parts.

For the purpose of illustrating the invention, I have disclosed a preferred application in which water is supplied and acts to continuously maintain an abrasive element in a cool state while grinding, but my invention is not necessarily limited to the feeding of water or to the particular structure herein set forth, which is intended merely by way of example of different possible adaptations.

In the drawing, 1 designates a conventional type of dental engine hand piece, and 2

is a metal tube provided with spring clips 3 by which it is detachably positionable on the hand piece 1, with its outer or discharge end located adjacent to the inner surface of the grinding wheel 4. The metal tube 2 forms part of the fluid conducting means, and to this end has its inner end bent outwardly to receive a flexible or rubber tube 5, the opposite end of said flexible tube being connected to an outlet 6 of the electrical valve controlling device which will now be described.

Said electrical device comprises an electro-magnet consisting of an outer coil 7, a core 8, and a vertically movable element in the form of a plunger 9 which is arranged within a housing 10. The lower end of said housing 10 is closed by a removable, threaded cap 11 which carries the aforementioned water outlet 6, and connecting with the upper end of the housing 10 is a tube 12 which leads upwardly through the core 8 to receive a vertical rod 13 that carries the plunger 9 and extends upwardly to a point above the top of the electro-magnet.

14 designates a valve seat arranged at the upper end of the tube 12, above the top of the electro-magnet, and 15 is the fluid controlling valve carried at the upper end of said rod 13 and cooperating with the valve seat 14. The valve 15 is preferably held in place on the rod 13 by a nut or other suitable removable device, which when taken off, permits the rod 13 and plunger 9 to be dropped downwardly, after first removing the cap 11, when repairs are required.

16 designates a coupling between the upper end of the tube 12 and a metal tube 17 connecting with a water supply pipe 18. 19 designates a manual cut-off valve, and 20 is a housing within which a strainer may be located. 21 is a clean-out plug for the coupling 16, and 22 is an adjustable needle valve for regulating the normal flow of water. The electrical device just described is intended to be mounted upon a wall, or at any other suitable point, and is provided with binding posts 23 by which connection is made to the motor circuit, while the flexible tube 5 leads from the outlet 6 on the electrical device to the dental engine hand piece.

Referring to Figure 4, 24 designates the motor for the dental engine, 25 designates the motor circuit, 26 the panel board through which connection is made to the

electro-magnet already referred to, and 27 is a hand switch for disconnecting the electrical valve controlling device when desired. 28 is the usual foot controlling switch for 5 the motor circuit.

The operation of the device briefly is as follows: In the position of the parts illustrated in Figure 2, the valve 15 is closed by reason of the motor circuit being open, 10 and the plunger 9 has fallen by gravity until the valve rests upon its seat. Upon closing the motor circuit to start the engine, the core 8 is energized and the plunger 9 thereby elevated, lifting the valve 15 off 15 from its seat and permitting water to pass through the tube 12 into the chamber 10, thence through the tubes 5 and 2 into contact with the grinding element 4. By regulating the valve 22, the supply of water can 20 be adjusted so that the grinding element 4 will be continually moistened and cooled by a thin film, but without causing any excessive water feed or splash, it being understood that the pipe 18 is connected with 25 the usual city water supply under pressure. Thus, the grinding element is always maintained in a wet state, while the engine is in operation, and immediately the engine motor circuit is opened, the core 8 is deenergized and the movable element 9 drops to its lowermost position and closes the 30 valve.

While I have described the invention with reference to a more or less particular embodiment, it is not limited to the details set forth, but may be modified in various ways without departing from the underlying features thereof or the scope of the following claims.

40 I claim:

1. A device for use with a dental engine comprising fluid conducting means, an electric motor for operating said engine, a valve governing the passage of fluid through said conducting means, and an electrical device in the circuit with said motor and operating automatically to open the valve when the motor is running and to release the valve when the motor is idle.

45 2. The combination with a dental engine

5 hand piece, of fluid conducting means including a tube that is detachably positionable on said hand piece, a valve governing the passage of fluid through said conducting means, an electric motor for the engine, and an electrical device automatically governed by said motor for controlling the valve.

3. The combination with a dental engine 60 hand piece, of fluid conducting means including a tube that is detachably positionable on said hand piece, a valve governing the passage of fluid through said conducting means, an electric motor for the engine, and an electrical device automatically governed by said motor and operating to open 65 the valve when the motor is running and to release the valve when the motor is idle.

4. The combination with a dental engine 70 hand piece, of fluid conducting means including a tube that is detachably positionable on said hand piece, an electric motor for the engine, an electrical device governed by said motor and comprising an electro-magnet having a vertically operating movable element, said fluid conducting means also including a tube extending through the center of said electro-magnet, and a valve carried by said vertically movable element and controlling the passage 75 of fluid therethrough.

5. The combination with a dental engine 80 hand piece, of fluid conducting means including a tube that is detachably positionable on said handpiece, an electric motor 85 for the engine, an electrical device governed by said motor and comprising an electro-magnet having a vertically operating movable element, said fluid conducting means also extending through the center of 90 said electro-magnet, a rod carried by said movable element and extending upwardly above the top of the electro-magnet, a valve seat located above the top of the electro-magnet, and a valve carried by said rod 95 and cooperating with the valve seat to control the fluid supply.

In witness whereof, I have hereunto signed my name.

FREDERIC J. HOFSCHEIDER.
